UNITED STATES PATENT OFFICE

149,973

DESIGN FOR A REARVIEW MIRROR

Doris Robins, Norwalk, Conn., assignor to The
Roberk Company, Norwalk, Conn.

Application February 15, 1947, Serial No. 136,943

Term of patent 7 years

(Cl. D14—6)

To all whom it may concern:

Be it known that I, Doris Robins, a citizen of the United States, residing in Norwalk, county of Fairfield, and State of Connecticut, have invented a new, original, and ornamental Design for a Rearview Mirror, of which the following is a specification, reference being had to the accompanying drawings, forming part thereof.

Figure 1 is a front elevational view of a rearview mirror, showing my new design.

Figure 2 is a rear elevational view thereof.

Figure 3 is an end elevational view thereof.

Figure 4 is a side elevation taken at right angles to Figure 2.

I claim:

The ornamental design for a rearview mirror, as shown.

DORIS ROBINS.
